UNITED STATES PATENT OFFICE.

BERTRAM K. HOLLISTER, OF CHICAGO, ILLINOIS, ASSIGNEE TO THE HOLLISTER-WILSON LABORATORIES, OF PORTLAND, MAINE, A CORPORATION OF MAINE.

SURGICAL LIGATURE.

1,239,690.

Specification of Letters Patent. Patented Sept. 11, 1917.

No Drawing.

Application filed June 14, 1917. Serial No. 174,719.

To all whom it may concern:

Be it known that I, BERTRAM K. HOLLISTER, a citizen of the United States, residing at Chicago, in the county of Cook and State 5 of Illinois, have invented a certain new and useful Improvement in Surgical Ligatures, of which the following is a specification.

The present invention relates to putting up in commercial form, surgical ligatures 10 commonly known as catgut. The prior practice in this art has been to first color the catgut if desired, then to immerse the same in a liquid having certain desired properties in tubes which are then sealed up and 15 sterilized. Various liquids have been proposed among which might be mentioned alcohol, chloroform, benzol, toluol, xylol and various other liquids supposed to produce certain desired effects. Water has 20 been employed in some instances, but without securing favorable results.

In the present invention, I place the catgut, which may be previously colored or otherwise treated if desired, in a glass tube, 25 with a particular liquid that has been found to give excellent results, and then seal the tube and sterilize the same, when it is ready to be placed upon the market.

As a base for the liquid in which to 30 serve the ligatures, I preferably employ a highly purified and deodorized kerosene, having an initial boiling point of not less than 140° C., and preferably about 150° C., to which I preferably add chloroform in 35 amount equal to about one third the volume of the kerosene.

To this material (or to the kerosene alone if the chloroform is to be omitted) is preferably added, oils which have particular 40 properties especially oils which are anti-septic and which have sufficient odor of their own to mask the characteristic odor always retained by kerosene, no matter how highly purified the same may be. As examples of such oils, I may employ oil of eucalyptus or oil of peppermint, for covering up the odor of kerosene, for which purpose about 1% may be employed. In addition to the above, I preferably also employ 45 an oil which acts as an anti-septic, the above oils being suitable for this purpose, as also is oil of pine needles. The amount of the anti-septic material may be about 5%. If desired, 5% of a mixture of the above mentioned oils may be employed.

In addition to the above materials, other oil-soluble antiseptics may also be employed, examples of these being thymol and menthol, which substances, if employed, are present in a relatively small amount, say 1 or 2%. 50

Prior to introducing the ligatures (previously stained if desired) into the mixture of kerosene and other materials, antiseptic and germicidal materials insoluble in oils may be employed by immersing the wet ligatures, in an aqueous solution of such antiseptic or germicidal material. The material known as "pyo-tannin" may be employed 55 for this purpose.

The use of chloroform alone has not given 60 entirely satisfactory results, this material readily decomposing, particularly upon 65 standing, and the preserved ligatures being injured by the decomposition products.

I make no claim to the use of hydrocarbons of the coal tar series, such as benzol, toluol, xylol and the like, as the use of the preservative liquid. Kerosene is found to be 70 very much better than the coal tar oils mentioned, this material acting as a local stimulant to increase the speed of healing of the wound. The addition of the eucalyptus oil, oil of peppermint or oil of pine needles also 75 act as stimulants in this respect, thereby increasing this function of the kerosene. 80

At the time of use of the ligature, after the tube has been broken, and the ligature removed, the chloroform rapidly evaporates, leaving the kerosene and some of the other substances mentioned above, which 85 substances, and particularly the kerosene render the ligature permanently pliable to a much greater degree than the liquids heretofore employed. This also to some extent prevents the new skin being formed from 90 very closely adhering to the ligature, hence the removal of the ligatures from the wound is less painful.

What I claim is:

1. A surgical ligature package comprising 100 a container and a ligature therein, the latter being immersed in a bath containing kerosene having an initial boiling point of not below about 140° C.

2. A surgical ligature package comprising 105 a container and a ligature therein, the latter being immersed in a bath containing kerosene having an initial boiling point of about 150° C.

3. A surgical ligature immersed in a par- 110

affin hydrocarbon distillate having a boiling point of not below about 140° C., and containing antiseptic materials.

4. A surgical ligature immersed in a par-
5 affin hydrocarbon distillate having a boiling point of not below about 140° C., and containing antiseptic oils.

5. A surgical ligature immersed in a par-
affin hydrocarbon distillate having a boiling
10 point of not below about 140° C., and containing antiseptic oils capable of masking the odor of said distillate.

6. Catgut ligature immersed in a liquid comprising refined kerosene.

11. 7. Catgut ligature immersed in a liquid comprising refined kerosene and chloroform.

8. Catgut ligature immersed in a liquid comprising refined kerosene, chloroform, and aromatic oils having antiseptic properties.

20

9. Sterilized catgut ligatures immersed in a liquid comprising about three parts kerosene and one part chloroform, together with a small percentage of oil of eucalyptus, oil of peppermint, oil of pine needles, menthol, 25 thymol, and the like.

10. A catgut ligature impregnated with oil-insoluble antiseptic material, and immersed in a liquid comprising kerosene.

In testimony whereof I have signed my 30
name to this specification.

BERTRAM K. HOLLISTER.
